UNITED STATES PATENT OFFICE.

FREDERICK G. OSBORN, OF NEWARK, NEW JERSEY.

CIGAR-PERFORATOR.

SPECIFICATION forming part of Letters Patent No. 243,153, dated June 21, 1881.

Application filed April 23, 1881. (No model.)

To all whom it may concern:

Be it known that I, F. G. OSBORN, a citizen of the United States, residing in the city of Newark, county of Essex, and State of New Jersey, have invented certain new and useful Improvements in Cigar-Perforators, fully described and represented in the following specification and the accompanying drawings, forming a part of the same.

10 My invention relates to an improvement in that class of cigar-perforators combining a cup-shaped shield and a piercing-tool; and it consists in a cigar-perforator formed of one piece of metal of cup shape, with a bent tongue cut from the side and projected into its interior.

In the drawings annexed, Figure 1 is a side view of my perforator applied to a cigar, the cup or shield being shown in section; and Fig. 2 is a perspective view of the perforator alone.

20 A is the cup or shield, whose use is to protect the point of the piercer, that it may be carried in the pocket, and which may be made of thimble or acorn or other suitable shape.

The piercer a consists of a pointed tongue 25 of metal cut from the side of the cup, with its point toward the mouth of the latter and its body twisted to give it firmness, as well as to bring the edge of the metallic tongue against the cigar when in use. By bending the tip of 30 the tongue partly toward the center of the cup the perforation is made at one side of the cigar rather than at the point, where it is most likely to split open the cigar-wrapper; and by mak-

ing the cup of such proportions that the cigar will not penetrate to the bottom all injury to 35 the tip of the cigar from either cup or piercer is effectually prevented. With the point bent to perforate the side of the cigar, as plainly shown in Fig. 1, a number of holes can be made by applying the piercer to different sides 40 of the cigar-tip, which would not be the case were the piercer arranged in the center of the cup.

By making the perforator of one piece of metal great cheapness is secured, and the article can be owned by every smoker and carried in the pocket conveniently.

I am aware that cigar-piercers have been patented with a guard and tool combined, as in Patents Nos. 133,864, of 1872, and 218,692, 50 of 1879; but in these inventions the elements of simplicity and cheapness presented in mine are wanting.

I therefore claim my invention as follows:

The cigar-perforator formed of one piece of 55 metal of cup shape, with bent tongue cut from the side and projecting in its interior, substantially as shown and described.

In testimony whereof I have hereunto set my hand in the presence of two subscribing witnesses.

FRED. G. OSBORN.
